UNITED STATES PATENT OFFICE.

WILLIS S. SHERMAN, OF MILWAUKEE, WISCONSIN.

DESIGN FOR AN AUTOMOBILE-HOOD.

No. 39,628.

Specification for Design.

Patented Oct. 20, 1908.

Application filed June 29, 1908. Serial No. 441,036. Term of patent 14 years.

To all whom it may concern:

Be it known that I, WILLIS S. SHERMAN, a citizen of the United States, residing at Milwaukee, in the county of Milwaukee and State of Wisconsin, have invented a new, original, and ornamental Design for Automobile-Hoods, of which the following is a specification, reference being had to the accompanying drawing, forming part thereof.

Figure 1 is a side elevation of an automobile hood, showing my new design and Fig. 2 is a front elevation thereof.

The invention consists of a casing or hood for covering the engine of an automobile and is approximately semicylindrical for its main part with a plain front end of substantially the configuration shown in Fig. 2 where a circular part at each side marks the location of a cylindrical member on each side of the

casing proper which slightly projects laterally therefrom as shown and constitutes a lamp or headlight casing. The front end of the hood is shown with a box like container beneath it and with a projection at its upper part in the form of a ventilator. As shown the front of the hood with its box like lower part has a network between the strips forming the outlines and the ornamental divisions which network in practice is a screen for admitting air to the interior of the hood.

I claim:

The ornamental design for an automobile hood, as shown and described.

WILLIS S. SHERMAN.
